UNITED STATES PATENT OFFICE

FRANK C. REILLY, OF NEW YORK, N. Y.

DESIGN FOR A BOTTLE OR SIMILAR CONTAINER

Application filed April 1, 1932. Serial No. 43,354. Term of patent 14 years.

To all whom it may concern:

Be it known that I, FRANK C. REILLY, a citizen of the United States, residing at New York city, in the county of New York, Borough of Manhattan and State of New York, have invented a new, original, and ornamental Design for Bottles or Similar Containers, of which the following is a specification, reference being had to the accompanying drawings, forming a part thereof,

I claim:

The ornamental design for a bottle or similar container as shown.

FRANK C. REILLY.
